US00D722069S

(12) **United States Design Patent**
Lee et al.

(10) **Patent No.:** **US D722,069 S**
(45) **Date of Patent:** ** Feb. 3, 2015

(54) **DISPLAY SCREEN OR PORTION THEREOF
WITH GRAPHICAL USER INTERFACE**

(71) Applicant: **Samsung Electronics Co., Ltd.**,
Suwon-si, Gyeonggi-do (KR)

(72) Inventors: **Jeong-Yeon Lee**, Seongnam-si (KR);
Heui-Jin Kwon, Seongnam-si (KR)

(73) Assignee: **Samsung Electronics Co., Ltd.** (KR)

(**) Term: **14 Years**

(21) Appl. No.: **29/471,056**

(22) Filed: **Oct. 28, 2013**

Related U.S. Application Data

(63) Continuation of application No. 29/390,710, filed on
Apr. 28, 2011, now Pat. No. Des. 692,444.

(30) **Foreign Application Priority Data**

Dec. 9, 2010 (KR) 30-2010-0053402

(51) **LOC (10) Cl.** **14-04**

(52) **U.S. Cl.**

USPC **D14/485**

(58) **Field of Classification Search**

CPC G06F 3/048; G06F 3/0481; G06F 3/0482;
G06F 3/04812; G06F 17/3084; G06F

17/30861

USPC D14/485-495

See application file for complete search history.

Primary Examiner — Kevin Rudzinski

(74) *Attorney, Agent, or Firm* — Cantor Colburn LLP

(57) **CLAIM**

The ornamental design for display screen or portion thereof with graphical user interface, as shown and described.

DESCRIPTION

The single FIGURE is a front elevational view of a display screen or portion thereof with graphical user interface, showing our new design.

The broken lines illustrating the display, display screen and portions of the graphical user interface form no part of the claimed design.

1 Claim, 1 Drawing Sheet
